UNITED STATES PATENT OFFICE.

FRIEDRICH WILHELM BRANDES, OF SOLVESBORG, SWEDEN.

DUSTLIKE FUEL.

No Drawing.

Application filed July 3, 1924. Serial No. 723,940.

To all whom it may concern:

Be it known that I, FRIEDRICH WILHELM BRANDES, a citizen of Sweden, and a resident of Solvesborg, Sweden, have invented 5 certain new and useful Improvements in Dustlike Fuel (for which I have filed application in Germany, May 9, 1923, Serial No. 109,624), of which the following is a specification.

10 This invention relates to dust like fuel, and it is intended to both improve the manufacture of this article as well as to convert suitable kinds of fuel into a state in which it may safely be shipped to great distances 15 in the powderous or dust-like condition and may be readily disintegrated substantially without loss at the place of consumption, and may be safely and reliably fed into the furnace or fire-place, while at the same time 20 substantially eliminating to a minimum the dangers heretofore occurring of back-firing, explosion, and blowing out of the flame. My invention among these and other important uses and advantages is also intended to materially 25 reduce the costs of transportation of such material and to simplify its mode of application, and in consequence thereof to also render the construction of dust fed furnaces and fire-places less complicated. Besides, inasmuch 30 as for the fuel of the kind referred to the question of transportation is of great commercial importance, the employment of such fuel becoming impractical by the comparatively excessive costs of transportation, my invention by materially reducing the costs 35 of transportation, provides means for the economical utilization of dust-like fuel. In accordance with my invention any suitable kind of fuel, including fibrous peat and the like is treated in such a manner, as to become directly and economically available for dust-fed furnaces. It has been known heretofore to dry and to disintegrate different kinds 40 of fuel suitable for use in dust-fed fire-places and the like, and, on the other hand, it has been known to produce bricks or "briquettes" from dust-like coal or coal breeze. In accordance with my invention the manufacture of such fuel bricks is carried 45 out in such a manner that the bricks obtained from the dried and disintegrated comminuted fuel have only such a degree of coherence and solidity imparted to them as to enable them to be sufficiently resisting 50 during transportation, while at the same time being readily disintegrated at the place of

consumption. This is effected by a suitable selection of the temperature, and possibly of the bitumen or adhesive if added, so that the agglutinating action of the bitumen is utilized only to such a degree, as will be necessary only for the preservation of the shape of the brick during transportation, the state of coherence of the particles of the brick depending chiefly upon the inter-engagement of its mechanical molecules. It has been found desirable in some instances to add from 2 to 8% of adhesive substance to cause the briquette to have the above qualities when pressed into shape. By means of the transportation and the various operations and handlings during shipment the texture of the bricks is naturally somewhat loosened, without, however, causing them to become entirely disintegrated.

At the place of consumption the bricks or other pieces of mouldings obtained from the fuel may be readily comminuted into dust, thus for instance, by means of a beater mill, an edge runner or the like, preferably constructed so as to operate as a blower, ventilator or the like, and by this means the dust obtained may be mixed with air, and may be directly fed as dust-like fuel into the furnace or fire-place. In case a grate-fire-place is provided in combination with the dust fed fire place for the purpose of igniting the dust flame, the grate may be fed with the solid bricks, while the dust-fed fire place will be supplied with the brushed or disintegrated bricks or pieces of moulding.

It is to be understood that the present invention is not restricted to the particular mode of execution mentioned by way of exemplification, and various means of procedure and forms of apparatus may naturally be employed, according to various conditions of application without deviating from the spirit of the invention as herein set forth in the appended claims.

I claim:

1. The method of preparing naturally un-agglomerated coal for transportation and subsequent use in a pulverized fuel-burner, which comprises comminuting said coal, temporarily forming the comminuted coal into briquettes for transportation, and subsequently comminuting the briquettes for use in the burner.
2. The method of preparing naturally un-agglomerated coal for transportation and

subsequent use in a pulverized fuel burner, which comprises comminuting the coal, applying heat and pressure to the comminuted coal to form it into temporary briquettes for transportation, and subsequently comminuting the briquettes for use in the burner.

subsequent use in a pulverized fuel burner, which comprises comminuting and drying the coal, temporarily forming the comminuted and dried coal into briquettes for transportation, and subsequently recomminuting the briquettes for use in the burner.

3. The method of preparing naturally unagglomerated coal for transportation and

FRIEDRICH WILH. BRANDES.
